UNITED STATES PATENT OFFICE.

DAVID E. ROSS, OF LA FAYETTE, INDIANA.

CURRENT-GENERATOR AND SPARK-DISTRIBUTER.

1,220,277.

Specification of Letters Patent. Patented Mar. 27, 1917.

Application filed January 25, 1916. Serial No. 74,233.

To all whom it may concern:

Be it known that I, DAVID E. Ross, a citizen of the United States, residing at La Fayette, in the county of Tippecanoe and State of Indiana, have invented certain new and useful Improvements in Current-Generators and Spark-Distributors, of which the following is a specification.

My invention relates to improvements in combined current generators and spark distributors whereby to produce the necessary current for the charge igniting sparks, at the proper cyclic time, in the operation of internal combustion engines.

One of the salient objects of my invention is to provide improved means for generating and distributing single electric impulses, at proper cyclic times in the operation of internal combustion engines, to effectuate ignition of compressed fuel charges in the cylinders thereof, in harmony with the reciprocation of the respective pistons, and coöperating means for predetermining the relative periods of time in which said impulses are to be produced, with respect to the excursions of the pistons of such engines, and in harmony with the velocity at which said pistons are moving.

Another object of my invention is to simplify the construction and operation of devices of this character by eliminating all commutators, spark coils, circuit breakers, condensers and other such contrivances usually employed and necessary in systems of this general character; to cheapen the cost of construction and to render the operation more reliable and dependable.

Other and further objects of my invention will be apparent, to persons skilled in the art, from a consideration of the following description when taken in conjunction with the drawings, wherein:

Figure 1 is an end elevation of the combined current generator and spark distributor, showing the shafts upon which the rotatable parts are mounted, in section taken on line 1—1 of Fig. 2.

Fig. 2 is a vertical central section, taken on line 2—2 of Fig. 1.

In all the views the same reference characters are employed to indicate similar parts.

In the specific embodiment, which I have chosen to exemplify my invention, 5 is the engine shaft of a four cycle engine, and 6 is the valve shaft, or other counter shaft, or it may be another shaft driven in harmony

with the engine shaft having a definite rotative relation to the shaft 5. 7—7 are bearings for the shaft 6. Secured to the shaft 6, by means of a set screw 8, or otherwise, is a sprocket wheel 9 which has twice the number of teeth as are contained in sprocket wheel 10, to which it is connected by a sprocket chain 11.

The arrangement in any event shall be such that any desired number of points on the respective rotary members shall pass simultaneously through a plane in which the axes of the respective members are located, so that the armatures will always cut the magnetic fields of the respective inductors.

The sprocket wheel 10 is in this embodiment, a part of the sleeve 12, but it may be a separate wheel rotatively secured thereto, by any suitable means. The sleeve 12 is loosely mounted upon an axially reciproitable sleeve 13, which is slidable upon the shaft 5, and which is positively driven by said shaft by means of a spline and feather 14. The sleeve 12 is spirally slotted, as at 16, and a screw threaded lug 17 passes through the sleeve 12 into the slot 16 so that when the sleeve 13 is longitudinally or axially moved, on the shaft 5, the stud 17, coöperating with the slot 16, has the effect of 85 to rotate the sleeve 12, in some respect proportional to the axial movement of the sleeve 13. The sleeve 13 is axially moved by means of a forked lever 18, preferably having roller projections 19, that enter a groove 20 between the two annular radial projections 21 on end of the sleeve 13. The lever 18 may be moved by a speed governor, manually or by any other suitable means for reciprocating the sleeve 13, for a purpose to be hereinafter described.

The sleeve 12 is radially enlarged, as at 22, to provide a hub, preferably of magnet steel, suitably drilled and preferably hardened.

Secured to the hub 22, at selected intervals are permanent magnet bars 23+ and 23—, as by means of rivets 24, or otherwise. Any suitable number of pairs of such permanent magnet bars may be secured to the hub or disk 22. In the particular embodiment I have illustrated two pairs of such bars located at diametrically opposite points.

After the hardened steel magnet bars 23+ and 23— have been suitably secured to the hub 22, they should then be magnetized to produce the most powerful magnets, the in-

tervening parts of the hub 22 affording a path for the magnetic flux or the yoke of the magnet.

The collar 25 is secured to the outer end of the shaft 5 by the screw 26. Mounted on the shaft 6 is a hub 27 preferably of soft iron, or steel, secured thereto, as by a set screw 28. The hub is reduced in width to provide an annular projection or disk 29, upon each side of which are magnet cores 30—31. These cores are made, preferably, of laminated strips of soft sheet iron secured together, as by rivets 32, and secured to the annular hub portion 29, by other rivets 33. Any suitable number of pairs of magnet cores, 30—31, may be placed at suitable intervals around the hub 29. In the particular exemplification there are four such pairs and in conjunction with the permanent magnets 23+ and 23—, which are connected to the hub 22, the device is adapted for operation with a four cylinder engine.

The hub 27 is laterally extended into a sleeve 34, which carries a sleeve or cylinder 25 of insulating material 35, upon which are mounted a series of current collecting rings 36, one for each cylinder of the engine. Bearing upon each of the rings 36 is a brush 37, held by a brush holder 38, and pressed into contact with the respective ring by a spring 39. The spark plug of each of the cylinders of an engine with which the device is to be used is connected to the brush holder 38 by the wire 40. The series of rings 36, through their brush holders 38, may be connected to the respective cylinders, in order of succession, in which they produce their respective power strokes. Surrounding the electro-magnet cores 30 and 31 are coils 30' and 31', respectively. The free terminals of coils 30 are preferably connected to the frame of the device, or engine, the other terminals 41, being each connected to one of the rings 36, thus each pair of magnet coils is connected to one of the rings 36 so as to transmit to the respective spark plugs the impulse which they will, in turn, generate, when passing its coöperating permanent magnet or inductor.

The operation of the device is as follows:—Assuming that the engine shaft 5 turns clockwise, as shown by the arrow in Fig. 1, the inductor 27 will turn in the same direction, but the proximate peripheries of the rotating elements will be driven in the opposite directions, as shown by the arrows of the respective elements. The permanent magnets, or inductors, will be rotated toward the right and the proximate electro-magnets or armatures, toward the left, thereby increasing the rate of speed of the passing current inducing elements beyond what it would be if one or the other were stationary, while the coöperating element was being rotated. Just before the inductor or

a given pair of permanent magnets comes coincident with the armature or a given pair of electro-magnets, a magnetic flux will pass through the cores of said electro-magnet causing an electrical impulse to be generated in the coils 30 and 30' thereof, which will be transmitted over the wire 41 through the respective rings 36 and over the wire 40 to the respective spark plug of the engine, causing the spark to pass between the contacts of the spark plug and thereby exploding the compressed charge within the particular cylinder of the engine. This action follows in proper cyclic sequence.

The generated impulses will normally be produced, with reference to particular positions of the engine speed shaft 5, and thereby with respect to the positions of the respective pistons within the cylinders of the engine. If it is desirable to have the impulse occur at an earlier or a later time, within the cyclic operation, the sleeve 13 is reciprocated by the lever 18, which operation will have the effect of rotating the sleeve 12 and the inductor, comprising the permanent magnets 23+, 23—, either forwardly or rearwardly, and coincidentally, the inducing element, or armatures mounted upon the hub 27, will be rotatively displaced in the opposite direction, so that the radial coincidence, or generating location of the two elements, will occur sooner or later, in accordance with the axial movement of the sleeve 13 and the consequent rotation of the sleeve 12 thereby. The rotative displacement of the armature element and the inducing permanent magnet element in opposite directions is accomplished by a very slight rotation of the sleeve 12, and therefore it is only necessary to move the lever 18, in reciprocating the sleeve 13, a very slight distance to effect the entire latitude of movement necessary for retarding or advancing the spark within the cylinders of the engine. As the armatures, or pairs of electro-magnets 30, 31 are equally spaced around the periphery of the hub 29, any rotative displacement of the element will effect the spark time in all of the cylinders proportionately.

For an engine having eight cylinders it is only necessary to double the number of electro-magnets 30, 31 and the number of pairs of permanent magnets 23+, 23—, or to change the relative speed of the inductor and inducing elements in proper relation, all of which will be clearly understood by persons versed in the art.

While I have herein shown a single embodiment of my invention for the purpose of clear disclosure it is manifest that many changes may be made in the general relation, disposition, configuration and size of the parts within the scope of the appended claims.

Having described my invention, what I claim is:—

1. In a device of the character described, for use with an internal combustion engine, 5 the combination with a rotatable permanent magnet inductor; of a rotatable armature; connecting means for rotating the said armature and inductor synchronously with each other and in harmony with piston 10 movement of an engine, so that proximate coincident current inducing parts move in an opposite direction and means for relatively displacing said parts to change the time of coincidence thereof. 15 2. In a device of the character described, for use with an internal combustion engine, the combination of a rotatable permanent magnet inductor; a rotatable armature; driving means, for rotating said armature 20 and inductor synchronously with each other and in harmony with piston movement of an engine, so that proximate coincident current generating parts move in opposite directions, and means for rotatably displacing 25 said parts with reference to said piston movement to change time of coincidence thereof, whereby to vary the time of the current impulse. 3. In a device of the character described, 30 for use with an internal combustion engine, the combination of a plurality of rotatable permanent magnet inductors; a series of separate and independent rotatable armatures; driving means for rotating said armatures and inductors synchronously with 35 each other and so that proximate coincident current generating pairs of inductors and armatures move in opposite directions, and means for rotatably displacing said respective pairs to change time of coincidence 40 thereof with respect to the driving means, to vary the time of the current impulses. 4. In a device of the character described, for use with an internal combustion engine, 45 the combination of a rotatable inductor element, comprising a hub having a pair of radially disposed permanent magnets attached thereto, one limb thereof on each side of the hub; a rotatable armature ele-
- ment, comprising a hub having a pair of 50 radially disposed electromagnets attached thereto, one limb on each side of the hub, a given armature arranged to pass through the field of a given magnet as they approach and recede from each other; rotatable driving connections between said inductor element and said armature element for synchronously driving them in opposite directions, when the armature is within the magnetic field of said inductor, and means for 60 rotatably and relatively displacing said inductor element and said armature element to cause coincidence of operation to occur at an earlier or later period, with reference to the driving means. 65 5. In a device of the character described, for use with an internal combustion engine, the combination with an engine shaft to be driven at engine speed; a counter-shaft; means for driving the latter in two to one 70 relation with said engine shaft; an inductor element, having half the number of inductors as there are cylinders contained in an engine with which the device is to be used, mounted on one shaft; an armature element, 75 having as many armatures as there are cylinders in an engine with which the device is to be used, mounted on the other shaft, each armature adapted to pass a given inductor once during each revolution of the armature 80 element; collecting rings mounted on the shaft carrying the armature element, one for each armature; brushes bearing on said rings for connection with the respective spark plugs of an engine with which the device is to be used; and means for relatively, 85 rotatably displacing said elements, to cause generation of current impulses at earlier or later periods with reference to the cyclic operation of the pistons of said engine. 90

In testimony whereof I hereunto set my hand in the presence of two subscribing witnesses.
